CASTING MAGNESIUM AND ALLOY THEREOF.

Application filed January 14, 1926. Serial No. 81,304.

While the present improvements relate more particularly to the casting of magnesium and so-called light metal alloys in which magnesium is the predominant constituent, it will be understood that the improved method and apparatus involved are equally adaptable for the casting of any similar readily oxidizable metal. The difficulties encountered in melting and handling in molten state magnesium or an alloy largely composed of this metal are well known and these difficulties are still present when it is attempted to introduce such metal into a mold in any process of casting. For example, when sand castings are made in the ordinary way by simply pouring the molten magnesium or light alloy metal into the sand mold, there is a very pronounced tendency for the metal to burn in the sprue. Even if the burning is not serious enough to prevent the cast article from being properly finished when removed from the mold, a certain loss of metal, due to oxidation, is inevitable, and of course the cleaner the casting, the more easily may the finishing operation be carried out.

It has heretofore been proposed to overcome these difficulties specifically in casting magnesium and alloys containing the same by dusting the mold prior to casting the metal with sulphur or equivalent material capable of giving off in contact with the molten metal a vapor which is more easily oxidizable than magnesium. This procedure, however, has the objection that it is obviously difficult correctly to gauge the amount of sulphur or equivalent material thus used, and particularly if an excess is applied to the surface either of the mold proper or the core, so much vapor may be generated that some of it becomes entrapped during the period that the metal is solidifying, the result being blow-holes or surface shrinks in the casting. Furthermore, the sulphur or equivalent material has to be applied or dusted onto the mold each time a fresh casting is poured and in any case the method in question is obviously not applicable where a metal mold is employed, because of the non-porous character of the latter.

By the present improved construction of mold we make it possible to supply to the mold cavity an inert or reducing gas, specifically sulphur dioxide, in an amount suf-

ficient to displace the air normally filling such cavity but without danger of sulphur vapor becoming entrapped and generating an excessive amount of gas at some point. It is further rendered possible to maintain a continuous supply of such inert or reducing gas while a succession of castings is being poured in the same mold.

To the accomplishment of the foregoing and related ends, the invention, then, consists of the steps and means hereinafter fully described and particularly pointed out in the claims, the annexed drawing and the following description setting forth in detail certain means and one mode of carrying out the invention, such disclosed means and mode illustrating, however, but one of various ways in which the principle of the invention may be used.

In said annexed drawing:—

The single figure there appearing is a central vertical section through a mold constructed and arranged to carry out our improved method.

The mold thus illustrated is specifically designed for casting a piston for an internal combustion engine or like hollow article of general cylindrical form. The mold part 1 will preferably be of metal, e. g. cast iron, as is commonly used in foundries at the present time for casting light metal pistons, but such mold may be made of sand, if desired. Such permanent mold has a cavity 2 that conforms with the exterior shape of the article to be cast and an enlarged space 3 continuous with the upper end of such cavity whereby a lateral offset 4 is provided that substantially encircles such cavity. In the angle of such offset a depression or groove 5 is cut, into which may be placed a suitable chemical substance, solid or liquid, that is adapted to volatilize by the heat of the mold and give off an inert gas that is heavier than air or that may be ignited and give off such a gas. The core 6, which may be either of sand or of collapsible metal parts, is of course separable from the mold 1 and is formed with an enlargement 7 at its upper end adapted to fit the enlarged portion 3 of the mold cavity, the shoulder 8 between such enlargement and the core proper resting on the offset 4 in the mold when the parts are properly assembled.

When thus in place, such shoulder will seal off the chamber 5 save for a slit-like

vent opening or openings 10 which are so narrow that molten metal will solidify before flowing therethrough into such chamber. The core is also provided with a central sprue 11, the lower portion of which communicates through a gate 12 with the mold cavity in which the casting is to be formed.

In operation, after the mold part 1 has been preliminarily warmed up, the gas producing material hereinbefore referred to is placed in the chamber 5, or a small quantity of sulphur is strewn around in such chamber and ignited. Then as the core 6 is put in place, the gas generated from such material is trapped and forced out through the vent 10 into the cavity 2, expelling the air through the gate opening 12 and sprue 11. When this has been accomplished, the molten metal is then poured into the mold in the usual manner. The material 13 in the chamber can be replenished from time to time in the case where a permanent mold part 1 is used. As an example of a material that will generate a suitable inert gas as a result of the heat derived from the mold, para dichlor-benzol may be named, although this material has the disadvantage that the gases generated are more obnoxious than the sulphur dioxide formed by burning sulphur, as also naphthalene, carbon tetrachloride, and fuel oil. In no case, however, does the material used thus to generate the neutral or reducing gas come into direct contact with the surfaces of the mold parts that define the casting.

There is, accordingly, no danger of an excessive amount of such gas being generated with resultant formation of blow-holes or surface shrinks.

Other modes of applying the principle of our invention may be employed instead of the one explained, change being made as regards the means and the steps herein disclosed, provided those stated by any of the following claims or their equivalent be employed.

We therefore particularly point out and distinctly claim as our invention:

1. In apparatus for casting a readily oxidizable metal, the combination of separable mold parts, one of said parts having a chamber normally open to the atmosphere wherein a non-oxidizing gas may be generated, and the other part being adapted, when in position for casting, to seal off such chamber save for a vent into the mold cavity.

2. In apparatus for casting a readily oxidizable metal, the combination of a separable mold and core, said mold having a chamber substantially encircling the cavity therein and normally open to the atmosphere and said core having a portion to seal off such chamber save for a communicating vent.

3. In apparatus for casting a readily oxidizable metal, the combination of a separable mold and core, said mold having a chamber substantially encircling the cavity therein and normally open to the atmosphere and said core having a portion arranged, when said core is in position for casting, to seal off such chamber save for a slit-like vent, the latter being so narrow that molten metal will solidify before flowing therethrough into such chamber.

4. In apparatus for casting pistons and other articles of general cylindrical shape from a readily oxidizable metal, the combination of a separable mold and core, said mold having a cavity conforming to the exterior shape of the article to be cast and an enlarged space continuous with the upper end of such cavity, whereby a lateral offset is provided substantially encircling such cavity, with a depression in such offset adapted to receive and contain a gas-generating material, and said core having a lateral shoulder fitted to such enlarged space in said mold to seal off such depression save for a slit-like vent opening into the mold cavity.

5. In apparatus for casting pistons and other articles of general cylindrical shape from a readily oxidizable metal, the combination of a separable mold and core, said mold having a cavity conforming to the exterior shape of the article to be cast and an enlarged space continuous with the upper end of such cavity, whereby a lateral offset is provided substantially encircling such cavity, with a depression in such offset adapted to receive and contain a gas-generating material, and said core having a lateral shoulder fitted to such enlarged space in said mold to seal off such depression save for a slit-like vent opening into the mold cavity so narrow that molten metal will solidify before flowing therethrough.

Signed by us this 7th day of January, 1926.

JOHN A. GANN.
JOHN E. HOY.
